UNITED STATES PATENT OFFICE.

BENJAMIN F. HEIMBACH, OF ALLENTOWN, PENNSYLVANIA.

DESIGN FOR BURIAL-CASKETS.

Specification forming part of Design No. 6,771, dated July 15, 1873; application filed April 25, 1873.

To all whom it may concern:

Be it known that I, BENJAMIN F. HEIMBACH, of Allentown, Lehigh county, Pennsylvania, have invented a Design for Burial-Caskets, of which the following is a specification:

My improved design for burial-caskets consists in the half-rounded shape which I give to the ends, which are flexed, and in the style of ornamentation adopted in the lid and body, together with the bevel given to the sides and ends.

To enable others skilled in the art to make and use the same, I will proceed to describe it, referring to the drawings, in which the same letters indicate the same parts.

In the accompanying drawings, A is a side view of the body of the casket, with offsets at b, where the end pieces begin. A bead, c, is placed around the body at the bottom thereof, and near the top is placed bead d, both beads being of wood and half round. E shows the ends, which are half round, and are flexed and beveled. F is the casket-cover, configu-rated with raised moldings, the members of the molding of the lid being an ovolo, g, a cove, h, fillet i, ovolo k, and cove l. M is a slide or cover over glass panel in lid, the ends of which are half round and the sides in the shape of an ovolo.

I claim—

The design for coffins, substantially as shown, the ends of both box and lid being rounded, the ends of the box inclining slightly outward from the bottom, the entire box surrounded by a half-round molding at the bottom and near the top, the lid about two-thirds as deep as the box, inclined inward from its lower edge, and its inclined outline composed of a series of moldings.

In testimony whereof I have signed my name to this specification before two subscribing witnesses.

B. F. HEIMBACH.
